TARGET AND CIRCUIT FOR STORAGE TUBES

Richard L. Snyder, Jr., Princeton, N. J., assignor
to Radio Corporation of America, a corporation
of Delaware

Application April 12, 1945, Serial No. 588,046

3 Claims. (Cl. 315—12)

1

This invention relates to cathode beam storage tubes and may be used in "radar" systems, as described in my application, filed June 20, 1945, Serial No. 600,498, which is now U. S. Patent No. 2,454,410 issued November 23, 1948, as well as in other types of circuits, such as described, for example, in the application of Max H. Mesner, filed October 19, 1944, Serial No. 559,469.

In storage tubes of the cathode beam type, charges proportional to received signals have been built up on-elements of a target by the action of an electron beam sweeping over them in one scansion and "wiped off" or neutralized in another scansion of the same beam. When this neutralization takes place, a signal is produced and impressed on an indicating device. This prior art storage tube has several disadvantages, chief among which is the introduction of transients into the amplifying system by the sudden change of velocity of the beam.

It is an object of my invention to construct a storage tube having one cathode beam gun for putting the signal on a target and an additional cathode beam gun for taking it off.

Another object of the invention is to scan the put-on beam of a storage tube at a higher rate over the target than that of the take-off beam.

Another object is to scan the put-on beam over the target to reduce the positive reference potential thereof with suppressed secondary emission in accordance with the received signal and to scan the take-off beam thereover to raise the potential to said reference potential by means of secondary emission.

Another object is to construct the storage tube target of a plurality of insulated conductors with arrangements for scanning both beams transversely across the conductors independently of each other.

Another object is to construct the storage tube target of a plurality of insulated conductors with arrangements for scanning the put-on beam transversely across one region of the conductors and the take-off beam transversely across another portion of the same conductors and at a different rate.

Other objects will appear in the following description, reference being had to the drawings, in which:

Figure 1 is a diagrammatic illustration of the tube.

Figure 2 is an elevation of a portion of the target and shield grids.

Figure 3 is a section taken on the line 3—3 of Figure 2, viewed in the direction of the arrows.

In Figure 1, the evacuated envelope and supporting structure of the elements in the tube are omitted, as these are well known and may be of any suitable material and design. The top gun 1 in this figure may have the usual cathode 2 and heater 3. Around the cathode is the grid 4 for

2

controlling the beam 5. This control member, as usual, consists of a cylinder of metal having a minute orifice in its end. This opening is greatly enlarged for illustrative purposes. The first anode 6 may be of standard metallic tubular construction, having a small orifice in the end adjacent the gun and an internal wall having a suitable opening for constricting the beam the desired amount. Adjacent the remote end of the first anode is positioned the second tubular anode 7 of somewhat larger diameter. Spaced horizontal deflector plates 8, 9 are positioned in a well-known way for horizontally scanning the beam across the target, the front plate being partially broken away to show the back one. A variable voltage, of saw-tooth form, is impressed between these plates to produce the horizontal motion of the beam, as well understood. Spaced vertical deflector plates 10, 11 are used to position the beam on the desired horizontal line L. For this purpose the vertical deflectors would have a constant direct current voltage. Parallel shield plates 12, 13 are positioned in front of the upper part of the target.

The target consists of a sheet of insulation 14, such as a thin sheet of mica, on which has been deposited parallel strips 15 of metal, for example silver, deposited by photographic process or by any other method. The strips are relatively narrow and are preferably spaced apart a distance equal to three times their width. Metal shield grids 16, 17 are positioned at the top and bottom of the target and have prongs 18, 19 extending between the strips 15 and are preferably of the same width as the strips, so that they may be spaced therefrom a distance equal to their own width. A signal plate 20 is positioned on the side of the mica plate remote from the gun and is connected to any desired indicating device 20', for example, the facsimile recorder disclosed in the patent of Charles J. Young, 1,848,862, March 8, 1932, though a visual indicator such as an oscilloscope may also be used.

In the lower gun 21 the lower anodes, the deflector plates and shields may have the same construction as in gun 1 and these parts have been given the same reference characters as similar ones in upper gun 1, except that the subscript a has been added thereto to distinguish the ones from the others. It will therefore be unnecessary to specifically refer to the parts. This gun scans the beam 5a over the bottom of the target at the line L' extending across the strips 15. The two guns 1 and 21 enclosed in the evacuated envelope (not shown) are electrostatically separated by a central shield plate 22.

The cathodes of both guns may have a negative potential of 1,000 volts, the first anodes about -800 volts and the second anodes have the positive ground potential. The shields 12, 13 and 16 may be 100 volts negative and the shields 12a,

13a and 17 100 volts positive. These are mentioned merely as examples.

One of the guns, say the top gun 1, will have a variable voltage applied to the horizontally deflecting plates 8, 9, such as from a saw-tooth generator 23 operating at the repetition frequency of an associated radar equipment, say 400 cycles per second. The other gun will have its similar plates energized by a saw-tooth voltage of some lower frequency, such as 2 cycles per second, which coincides with the scanning frequency of the recording device 20'.

The operation may be described as follows:

A signal pulse, sent out at the start of each cycle of the saw-tooth generator 23 by a keyer and transmitter T, is reflected by aircraft, ships and other objects back to the receiver 24, in which the echoes are amplified and detected in known manner. These devices may be of any known type and are illustrated in block diagram. The antennae are preferably of the directional type, such as dipoles indicated. The detected and amplified signals modulate the beam 5 of gun 1 as it sweeps across the strips 15 along line L. The electrons of beam 5 landing on the floating elements 15, which have been previously charged to a positive reference potential, as later described, diminish the positive charge. The diminishing of this charge (or the driving of the elements negative) occurs when the beam strikes these elements because the shields 12, 13 and 16 are negative relative to the floating elements and, therefore, suppress the emission of secondary electrons released by the impact of the beam. The repeated scanning of the mosaic by this put-on beam increases the charge due to signals on each successive cycle. The charges induced by noise in the signal which does not occur at the same point in successive cycles is smoothed out.

While the storing of the signals by beam 5 goes on without interruption, the take-off and reproducing beam 5a of the lower gun recharges at each sweep the floating elements to a positive reference potential determined by the shields 12a, 13a and 17. The recharging is accomplished by means of secondary emission from the floating elements. When the beam 5a strikes the elements, it releases a preponderance of secondary electrons. These electrons are attracted by the positive fields of the shields until the potential of the elements rises to that of the shields. When this occurs, a collecting field no longer exists around the elements and the secondary emission ratio falls to unity. The reproducing beam 5a is sufficiently intense to over-ride in one sweep any signals which may have been recorded by the beam 5 of the upper recording gun in its multiplicity of sweeps.

When the take-off beam 5a recharges the strips 15 to reference potential, as just described, signals are impressed on recorder 20'. If the echoes or signals are from a moving object, such as an airplane, for example, they will be recorded as a diagonal line across the page of the facsimile recorder, but those from stationary objects will have unchanging phase and will be recorded in vertical lines on the page.

It will thus be seen that, in my improvement, the strength of desired signals is built up by storage before being recorded, but noise signals are not, since they occur at random.

The storing and discharging of the signals may be opposite to that described, but the results are not so satisfactory. When the put-on beam is thus used to scan the elements of the target in

the region of a positive collecting field to impress a positive charge thereon by virtue of emission of secondary electrons and the take-off beam scans them in a negative field to charge the elements to a negative potential, then the stored signal will vary with variations in secondary emission ratio from element to element in the storing process. In the preferred method, any variation in emission ratio is, however, not objectionable in the take-off action, as the secondary emission ratio of the elements is necessarily made greater than unity and the take-off beam is made strong enough to over-ride any charge impressed by the put-on beam.

Various other modifications may be made without departing from the spirit of the invention.

Having described my invention, what I claim is:

1. In cathode beam storage tubes, a target 20 consisting of a sheet of insulation, a multiplicity of electrically isolated conductors of relatively high secondary electron emissivity extending across said sheet and a shield grid at each end having prongs extending between the conductors 25 and spaced therefrom.
2. In cathode beam storage tubes, a target consisting of a sheet of insulation, a multiplicity of electrically isolated conductors of relatively high secondary electron emissivity extending across 30 said sheet, a shield grid at each end having prongs extending between the conductors and spaced therefrom, means for applying a higher voltage to one grid than to the other, means for scanning a beam at a predetermined 35 rate across said conductors adjacent one grid and means for scanning another beam across said conductors adjacent the other grid at a rate relatively lower than the first-mentioned rate.
3. In cathode beam storage tubes, a target consisting of a sheet of insulation, a multiplicity of electrically isolated conductors of relatively high secondary electron emissivity extending across 40 said sheet, a shield grid at each end having prongs extending between the conductors and spaced therefrom, means for applying a higher voltage to one grid than the other, means for scanning a beam at a predetermined rate across said conductors adjacent one grid and means for scanning a beam across said conductors adjacent the 45 other grid at a rate relatively lower than the first-mentioned rate, said last-mentioned beam being of higher current than the first-mentioned beam.
